(57) **CLAIM**

The ornamental design for a laser, as shown and described.

DESCRIPTION

FIG. 1 is a front perspective view of a laser showing my new design;

FIG. 2 is a right view thereof;

FIG. 3 is a left view thereof;

FIG. 4 is a front view thereof;

FIG. 5 is a top view thereof;

FIG. 6 is a bottom view thereof; and,

FIG. 7 is a back view thereof.

Any broken lines present are indicative of environmental structure in the drawing and are not part of the design sought to be patented.
